DESIGN FOR A VENDING MACHINE

Carl Louis Otto, New York, N. Y., assignor to C.
Earl Hovey, Kansas City, Mo., trustee

Application August 4, 1945, Serial No. 121,229

Term of patent 14 years

(Cl. D52—3)

To all whom it may concern:

Be it known that I, Carl Louis Otto, a citizen of the United States, residing at 580 Fifth Avenue, New York city, in the county of New York and State of New York, have invented a new, original, and ornamental Design for a Vending Machine, of which the following is a specification, reference being had to the accompanying drawings, forming a part thereof.

Fig. 1 is a perspective view of a vending machine, showing my new design.

Fig. 2 is a top plan view of the portion shown in full lines in Fig. 1; and

Fig. 3 is an end elevational view of Fig. 2.

The dominant feature of the design resides in the portions shown in solid lines in the drawings.

I claim:

The ornamental design for a vending machine, as shown and described.

CARL LOUIS OTTO.
